UNITED STATES PATENT OFFICE

2,574,205

Fixture Hanger

Francis H. Blumenthal, Los Angeles, Calif., assignor to West Coast Fittings Co., Los Angeles, Calif., a corporation of California

Application August 9, 1948, Serial No. 43,277

2 Claims. (Cl. 4—170)

1

This invention relates to adjustable hanger supports for basins, kitchen sinks, laundry tubs and the like, and more particularly to an improved and more universal adjustable hanger support over that disclosed in United States Patent No. 2,083,271, issued June 8, 1937, to Jack Lindenbaum, commonly owned with the instant application by West Coast Fitting Co., a California corporation.

Some forms of kitchen sinks, laundry tubs, wash basins, and the like fixtures, collectively referred to herein as basins, are made of porcelain or the like vitreous material and are provided with integral recesses, pockets or sockets for the reception of an upwardly and outwardly projecting lug intended to be secured to a wall or the like for hanging such basins.

Other forms of basins or fixtures, generally made of and referred to herein as cast iron basins, are generally coated with vitreous china, porcelain, or like material and are provided with integrally cast downwardly and outwardly depending lugs or the like for accommodation in complementary female bracket members similarly intended to be secured to a wall for hanging the same.

As is disclosed in the patent above referred to, it was theretofore the practice to provide for each form of fixture and for each size of the same (varying among different manufacturers) hanger brackets and supports of both male and female variety of differing lengths corresponding with the divergent measurements of the wide range of available fixtures. A wide variety of lugs must therefore be kept on hand or separately purchased, and in addition the strength in use and adaptability to differing places of installation was deficient.

It is therefore an object of the instant invention to provide a universal hanger adaptable for male and female lugs and recesses, respectively, found upon the two major types of basins above referred to, which combine features of longitudinal adjustability and strength and desired features of adaptable securing of the same to variously spaced and located studs or to other points of necessary securing to a wall or similar surface.

It is another object of the invention to provide a universal hanger for basins or the like having the desired characteristics herein described which may be readily cast integrally preferably in two parts having universal male and female hanger elements formed therein.

Another object of this invention is the provision of new and improved combined male and female basin-engaging means, the same being adaptable for all conventional basins regardless of size or type as now commonly constructed.

Other objects of the invention are the provision of improvements over prior art devices

and structures heretofore employed to accomplish a generally similar or more limited purpose, simplicity of design, economical in manufacture and strong and practical in use.

With these and other objects in view, the invention consists in the construction, arrangement and combination of the various parts of the device whereby the objects contemplated are attained, as hereinafter set forth, pointed out in the appended claims and illustrated in the accompanying drawings.

In the drawings:

Figure 1 is a front view of a preferred form of hanger selected as embodying this invention.

Figure 2 is a sectional view taken as on a line 2—2 of Figure 1.

Figure 3 is a vertical sectional view as on a line 3—3 of Figure 1.

Figure 4 is a sectional view as on a line 4—4 of Figure 1.

Figure 5 is a view as on a line 5—5 of Figure 4 and showing the back side of the hanger corresponding to the right-hand end of Figure 1.

Figure 6 is a view similar to Figure 4 showing the hanger as used in an inverted position.

Figure 7 is a front view of another preferred form of the invention.

Figure 8 is a sectional view as on a line 8—8 of Figure 7.

Figure 9 is a top view of the same.

Figure 10 is a view similar to Figure 8, but showing the hanger of Figure 8 applied to a vitreous fixture.

Referring more particularly to the drawings, there is illustrated, by way of example and not of limitation, a bracket generally designated by the numeral 20 having right and left complementary members 21 and 22, respectively, providing in substance sockets 23 and 24 for the reception of corresponding complementary male lugs 25 in Figure 4, as upon an iron type of fixture indicated at 26 in said figure.

On the other hand projecting tongues 27 extend upwardly and outwardly from the right-hand and left-hand members 21 and 22 and may include any reinforcing ribs as indicated at 30. In Figure 6 one of said lugs 27 is shown, briefly speaking, in an upwardly projecting outwardly extending position relative to a wall 33 for its accommodation in a complementary recess 34 of a vitreous type of basin or fixture illustrated at 35 whereby to support the same.

In more detail, the halves 21 and 22 of the bracket may comprise male arms 36 and female arms 37, the latter being optionally channeled at 38 for the slidable nesting reception of the male arm 36. Said male arm may also be formed with a slot 40 and a shoulder formed by an under-cut 41 therearound to receive the head, not shown, of a nut securable to a bolt engageable through said slot 40. Any number of ap-

propriately placed counter-sunk bolt holes 42 and 50 are also provided on said arms and elsewhere as desired.

The arms 36 and 37 in the present invention may be transversely notched or weakened as at 45 and 46, respectively, in order that the portions of the arms 36 and 37 between said notches and the ends 48 and 49 may be broken off to shorten the overall longitudinal dimension of the bracket.

In the embodiment of Figures 1 through 6, above described, screws, bolts or the like may be extended as through the holes 42 or 50 for securing of the bracket to the wall at appropriate points corresponding with the positions of the studs or other strong points.

Referring now to the other preferred form of the invention, as illustrated in Figures 7, 8, 9 and 10, there is shown a bracket having a pair of longitudinally adjustable preferably telescoping arms 100 and 101 upon bracket members 102 and 103. The arms, being similar to those heretofore described in connection with the first preferred embodiment of Figures 1 through 6 and being further described in the patent above referred to, are herein for the most part designated by like reference numerals to those applied for the first embodiment.

Each of the members 102 and 103 may be formed with upstanding lugs or male members 105 and 106 which, optionally reinforced as by any webs 107, normally extend outwardly and upwardly as from a vertical wall surface 109.

The arms adjacent the lugs 105 and 106 may define shoulders 110 on one side of the lugs while bracket portions 111 may likewise form opposed shoulders 112 on the opposite or outer side thereof. Thereby, marginal edges 114 and 115 of the lugs or intermediate tongues 105 and 106 are free and spaced, by cutout portions 13, relative to said shoulders 110 and 112 although defining pockets therewith, as between opposite shoulders 110 and 112, the inner surface 117 of the lugs 105 and 106 and a wall 109.

Having reference to Figure 8 it may be seen that if the socket area 121, as above defined, is used for the reception of a lug element 122 depending from the back of an iron type basin 123, said socket 121 will serve a function corresponding to that of the sockets 23 and 24 of the first embodiment, and such male lug will be confined against lateral movement by the shoulders 110 and 112 while being held against the wall 109 by the lug 114.

On the other hand, if it be desired to employ the second preferred structure upon the vitreous type of basin, the lugs 105 and 106 comprising male elements may be utilized in a similar manner to that indicated for the lugs 27 of the first embodiment and may be inserted into the recess or pocket 130 (Figure 10) thereof.

The shoulders 118 and 119 are of such a height that they engage the tip 124 (e. g., Fig. 8) of the depending fixture lug 122 to prevent sidewise movement but are not so high as the lugs 105 and 106. If desired, the lower edge 131 (Fig. 10) of the socket structure can be permitted to rest upon the shoulders 118 and 119 (e. g., Fig. 7) the latter thereby in effect defining horizontal shoulders. Otherwise these horizontal shoulders may be weakened as along lines 126 and 127 similarly to the arms at 46 to permit their removal when the hanger is to be used for vitreous fixtures

(Fig. 10), thereby making the lugs 105 and 106 relatively longer.

It is therefore apparent that a hanger of universally adapted nature has been created of remarkably simple construction considering its broad use, which is compact and complete, needing no duplication or supplementation by auxiliary devices for hanging any type of vitreous or iron basin.

10 This invention features the provision of a universal fixture hanger of improved type capable of accommodating both male and female basin supporting constructions of any size and of a type normally built into such basins. In particular it features improvements in the disclosure of United States Letters Patent No. 2,083,271, furthering the purpose of the same by an improved construction particularly residing in the form and more universal adaptability of the basin engaging members, to wit, the tongue, lug, or socket construction.

15 Although the invention has been herein shown and described in what is conceived to be the most practical and preferred embodiment, it is recognized that departures may be made therefrom within the scope of the invention which is not to be limited to the details disclosed herein but is to be accorded the full scope of the claims so as to embrace any and all equivalent structures.

20 The invention having been herein described, what I claim as new and desire to secure by Letters Patent is:

25 1. In a support for a cast iron type of basin or the like, comprising two socket members for reception of complementary hanging lugs, conventionally provided in such forms of basins, the improvement comprising said socket members being formed with spaced cut-out portions defining intermediate tongues projecting laterally from said support for engagement in complementary recesses conventionally formed in porcelain type basins.

30 2. In a support for a cast iron type of basin or the like, comprising two socket members for reception of complementary hanging lugs, conventionally provided in such forms of basins, the improvement comprising said socket members being formed with spaced cut-out portions defining intermediate tongues projecting laterally

35 from said support for engagement in complementary recesses conventionally formed in porcelain type basins, said spaced cut-out portions defining, with the upper edge of the adjacent body of the support, horizontal shoulders raised

40 above said upper edge and vertical shoulders spaced from said tongue, said horizontal shoulders being undercut and weakened along a horizontal line whereby they may be broken off for the purpose described.

45 3. In a support for a cast iron type of basin or the like, comprising two socket members for reception of complementary hanging lugs, conventionally provided in such forms of basins, the improvement comprising said socket members being formed with spaced cut-out portions defining intermediate tongues projecting laterally

50 from said support for engagement in complementary recesses conventionally formed in porcelain type basins, said spaced cut-out portions defining, with the upper edge of the adjacent body of the support, horizontal shoulders raised

55 above said upper edge and vertical shoulders spaced from said tongue, said horizontal shoulders being undercut and weakened along a horizontal line whereby they may be broken off for the purpose described.

60 4. In a support for a cast iron type of basin or the like, comprising two socket members for reception of complementary hanging lugs, conventionally provided in such forms of basins, the improvement comprising said socket members being formed with spaced cut-out portions defining intermediate tongues projecting laterally

FRANCIS H. BLUMENTHAL.
